UNITED STATES PATENT OFFICE.

SEYMOUR H. WENTZ, OF EAST ORANGE, NEW JERSEY.

DOUBLE-PLUG CONNECTER FOR ELECTRICAL CIRCUITS.

Application filed November 28, 1922. Serial No. 603,765.

To all whom it may concern:

Be it known that I, SEYMOUR H. WENTZ, a citizen of the United States, and resident of East Orange, in the county of Essex and 5 State of New Jersey, have invented certain new and useful Improvements in Double-Plug Connecters for Electrical Circuits, of which the following is a specification.

This invention relates to a circuit connector which has plug terminals adapted for insertion in the push-plug sockets of any ordinary wall outlet, or of lamp-socket plugs, and also has two pairs of sockets, so that by inserting this connector instead of 15 an ordinary plug, two plug-circuit connections may be made to one outlet or other circuit fitting, instead of one.

An important object of the invention is to provide a connector of this type which is 20 very simple, consisting of very few parts, and which may therefore be manufactured very economically, and which at the same time is strong and durable, and provides satisfactory insulation for the enclosed conductors.

Another object is to arrange such an appliance so that certain parts may be made in exact duplicate, which further reduces the manufacturing cost.

30 The characteristics and advantages of the invention are further explained in connection with the following detail description of the accompanying drawings, which show one exemplifying embodiment of the invention. After considering this embodiment, persons skilled in the art will understand that variations may be made within the principles of the invention; and I contemplate the employment of any structures that 35 are properly within the scope of the appended claims.

In the drawings:

Fig. 1 is a side elevation of the connector or plug, positioned for insertion in a wall 45 outlet or screw plug socket, also showing an ordinary push plug positioned for insertion in one branch or outlet of the connector.

Fig. 2 is an end view of the appliance.

Fig. 3 is an inside view of one of the 50 body sections with the conductors in position therein.

Fig. 4 is a perspective view of one of the combined conductor, plug terminal and terminal clip members.

55 Fig. 5 is a detail perspective view showing the bridging of the two conductors.

The body B of the appliance is made in two sections 1 which may be exact duplicates. The two sections have flat inner faces 2 which meet in the vertical center 60 plane of the appliance, as best shown in Fig. 2; and the two members are secured together by screws or rivets passing through holes 3 after the conductors have been inserted.

Each section of the body is formed so 65 that when two sections are put together in the manner described, the complete body has two branches or outlets 3, each of which is adapted to receive an ordinary push-plug P, Fig. 1. In order to receive the push-plug 70 terminals p, each branch 3 has two sockets s and s', each socket being formed jointly by channels in the two body sections as presently explained.

The body sections are formed of any suitable insulating material. In some cases they may be of porcelain or other suitable vitreous material, but in a great many preferred cases the body sections are of molded 75 synthetic resins which are familiar in the art under various trade names.

In each branch 3 of each body section, as best shown in Fig. 3, is a relatively wide channel 4 usually having parallel side walls, this channel forming one half of the socket s 80 in this branch of the body. Similarly, each branch has a channel 5 forming one half of socket s' in this branch of the completed body, as shown in Fig. 2. Toward the upper end each of the channels 4 may be of reduced 85 width and is curved towards the center line of the body section, as at 6, and at a point somewhat away from the center line (which is sufficiently indicated by the centers of the rivet holes 3) the channel portion 6 is intersected by a channel 7 leading to the upper flat surface 8 of the body section. Adjacent 90 to the point of intersection of channel portions 6 and 7, a continuation of the channel section 6 of increased width is formed, as at 9. A narrower extension 10 of channel section 9 crosses the center line of the body section and continues on downward, merging 95 with the upper end of the channel section 5 in the opposite branch of the body section. When the two identical body sections are put together to form a complete 100 body, the channel arrangement above described produces two continuous interior passages, parts of each of which constitute 105 one of the sockets s and one of the sockets s' in the opposite branch of the body; these

110

two passages intersect and cross at the center line of the body, and each passage has a branch 7 extending up through the upper flat body surface 8.

- 5 Combined conductor and terminal clip members 12 are provided, two of them being used in each of the appliances. These members are desirably made of thin flexible sheet metal having considerable "spring" such as 70
 10 copper or copper alloy, and they may be stamped and pressed into the form shown in Fig. 4 by a single set or series of dies, since the two members 12 employed in each appliance may be exact duplicates of each other. Each of these conductors has a curved portion 13 conforming generally to the shape of one of the channels in the body sections. At one end a portion 14 of the strip is bent back to form a clip to cooperate with one of the plug terminals *p* of any suitable or standard push-plug *P*, and similarly at the other end of the strip 13 a portion 15 is bent back to form a clip to cooperate with a plug terminal. Each of these spring clips desirably is formed with a shallow knob or projection 16 adapted to snap into a socket or hole 17 usually provided near the end of the plug terminal *p*. At a point substantially corresponding with the intersection of the body channels when the conductor member is placed in the body, as shown in Fig. 3, a notch 18 is cut out of the strip. The conductor member as shown in Fig. 4 is in substantially the proper position to insert in one of the channels of one of the body sections, and when the position of the conductor is reversed, it is adapted to fit in the other body section channel, and when two conductors of identical form are 85
 15 thus arranged and placed in the body channels as shown in Fig. 3, the notches 18 correspond so that there is an ample air gap at all points between the metal of the two conductors where they cross each other, this gap providing ample insulation. When the conductors are placed as described, the clip 14 of one conductor is located in one of the socket channels 4 of one branch of the body section, and the other clip 15 of that 90
 20 conductor is located in the socket channel 5 of the opposite branch of the body section. In this way yieldable or spring clips for two plug terminals *p* are provided in each branch of the appliance.
 25 A push terminal 20 consisting of a strip of suitable sheet metal usually thicker and stiffer than the conductor strip 12 is provided for each conductor, one end of this terminal being bent at a slight angle to provide a member 21 which is riveted to the conductor in such a position that the terminal 20 will extend through one of the body channels 7 when the conductor is placed in the body in either of its possible 95
 30 positions.

When the body sections and conductor pieces with their terminal projections have been assembled either by placing both of the conductor members in one body section as shown in Fig. 3, or by placing one conductor member in each body section in appropriate positions, the two body sections are brought together as shown in Fig. 2, whereupon the channels and conductors cooperate or correspond in the manner previously 75 sufficiently described; and the assembly is then completed by inserting rivets or screws, as also previously explained.

The appliance may be inserted in any wall plug terminal or a push-plug-socket which 80 is screwed into a lamp socket, as sufficiently indicated in Fig. 1, and two ordinary or standard push-plugs *P* may then be inserted in the branches of the appliance, or of course only one of them may be used at a time, as 85 may be desired.

The appliance as constructed in a preferred form, as herein shown, may consist therefore of only two principal parts, each duplicated, or four principal parts in all, 90 that is to say, two of the complete conductor and terminal members as shown in Fig. 4, and two of the body sections shown in Fig. 3. Of course in a convenient method of manufacture, each conductor member comprises two parts, that is, the strip 12 and the terminal 20, but these are preferably assembled to form a complete operative unit 95 as shown in Fig. 4, and these units are then inserted in the body sections in the manner previously described. By reason of the very small number of parts and the duplication of parts in each appliance, the device may be very cheaply manufactured with a very 100 moderate expense for manufacturing equipment such as molds and dies.

I claim:

1. A connector for electrical circuits comprising duplicate body sections of insulating material secured together and having 110 cooperating internal curved passages, and duplicate conductor members located in the passages, the conductor members being formed of sheet metal strips curved to conform to said body passages, the strips having mating notches to provide an insulating clearance where the two strips cross, the strip ends being folded back in opposite directions forming spring clips cooperating 115 with end portions of the body passages to provide two pairs of sockets, each pair adapted to receive the terminals of a push-plug, the conductors also having terminal members extending from the body and adapted to enter the sockets of an ordinary push-plug-socket or wall outlet.

2. A double outlet plug comprising two body sections of insulating material and of substantially identical form secured together 120 with inner flat faces in contact, each body 125

section having two intersecting channels depressed in its inner face, an end portion of each channel constituting a substantially straight socket portion and intermediate parts of each channel having a substantially curved formation, the channels in the two body sections cooperating to provide two intersecting body passages and two pairs of plug-terminal sockets, a conductor strip of spring sheet metal located in each of the body passages, each end of each strip having a deflectable clip portion located in one of the body sockets, the strips being provided

with cooperating notches to provide insulating clearance at a point corresponding with the passage intersection, each conductor having an operatively-integral push terminal extending outward through a branch of a body passage to provide a pair of terminals to cooperate with an ordinary plug-socket or wall outlet, the conductor members being substantial duplicates.

Signed at New York, in the county of New York and State of New York, this 27th day of Novbr., A. D. 1922.

SEYMOUR H. WENTZ.
